UNITED STATES PATENT OFFICE.

IRVING KAUFMAN, OF BALTIMORE, MARYLAND.

MARKING-TAG.

No. 895,469.

Specification of Letters Patent.

Patented Aug. 11, 1908.

Application filed March 3, 1908. Serial No. 418,942.

To all whom it may concern:

Be it known that I, IRVING KAUFMAN, a citizen of the United States, residing at Baltimore city, State of Maryland, have invented 5 certain new and useful Improvements in Marking-Tags, of which the following is a specification.

My invention relates to marking tags and more particularly to that class of tags which 10 are designed to be attached to textile fabrics and other similar articles of merchandise and to have written on them the numbers, cost and selling prices, and like memoranda relating to the article to which they are attached.

It has for its object the production of a tag 15 which may be quickly and securely attached to and easily removed from the fabric, and whose attaching devices are thoroughly housed when the tag has been attached, 20 thereby rendering it impossible for the device to scratch or wound the hands in the handling of the merchandise.

The tag has for a further object the capability of subsequent use, as it can be removed 25 without mutilation.

With the foregoing objects in view, my invention consists in certain novel features of construction and combination of parts, which will be hereinafter described and 30 pointed out in the claims.

In the accompanying drawings, Figure 1 is 35 a side elevation of the tag showing the same applied; Fig. 2 is a perspective view of the tag in position to be applied; Fig. 3 is a sectional view drawn to a greatly enlarged scale through the fastening device; Figs. 4 and 5 are perspective detail views of the female and male members of the locking device respectively. Fig. 6, is a face view of a modification, and Fig. 7 is a plan view of the disk used 40 for locking the male member to the tag.

My improved tag is preferably formed of a single strip A, of heavy paper or other suitable material, creased at its middle to form 45 the flaps 1 and 2, which flaps are of about equal length. The equality of the respective lengths of the flaps is not, however, essential to the invention, and they may be unequal lengths if desired. On the front side of 50 the tag is printed any desired form; as shown and designated 3 in Fig. 1.

In the free end of the flap 1 is secured the male member 4 of the fastening device, which member consists of a rivet having a 55 pointed stem 5, the stem being swelled below the point at 6, providing an annular

shoulder 7 thereon. The stem is cut away below the annular shoulder 7, at 8, forming the square shoulder 9, and 10 represents the usual head or flange of the rivet.

The member 4 is inserted through the free end of the flap 1 and is permanently secured therein by means of the disk 11, which disk is slit at 12 and provided with a central opening 13, the pointed stem 5 being inserted through central opening 13 of the disk and by reason of the disk 11 being slit at 12, it will spring over the swelled portion 6 of the stem 5 and spring back into locking contact under the shoulder 9 on the stem, thereby securing the 70 flap 1 between the head 10 of the rivet 4 and disk 11.

The female attaching member 14 is in the form of a hollow rivet and is provided with a cylindrical stem portion 15, having an opening 16 in the upper end thereof, the lower end portion being bent outwardly to form a circumferential flange 17. The lower three quarter part of the said cylinder portion, as well as the flange is split into six or more sections by means of the slits 18, which afford resiliency at the mouth or socket 19 and also serve as to render the cylindrical portion 15 easily collapsible as indicated in Fig. 3, within the cap or cover 20.

The female member 14 is secured on the flap 2 by reason of a suitable opening (not shown) being provided therein through which the cylindrical portion 15 is inserted with the flange 17 flush against the inner side 99 of the flap 2. The cap or cover 20, is then placed over the opposite end of the cylindrical portion on the opposite side of the flap, and a downward pressure is then applied by any suitable tool (not shown) and the cylindrical stem 15 is collapsed within the cap or cover 20, thereby securing the female member 14 to the flap 2, the cap or cover 20 affording a housing to the point 5 of the male member.

In the modification shown in Fig. 6, I have shown two of the attaching devices secured on a tag instead of but one, as it is oft times necessary to use more than one where the tag required is of very large dimensions in order 105 to prevent the ends from curling.

My device is operated as follows: The fabric B is inserted between the flaps 1 and 2 of the tag A, with the stem 5 of the male member 4 opposite the socket 19 of the female member 14. Pressure is then applied to the male member and by reason of the

2
stem 5 being pointed it will easily pass through the fabric, thence into the socket 19 of the female member 14. The socket being resilient will permit the swelled portion 6 of the male member to extend thereto and will lock under the annular shoulder 7 thereon, with the point 5 of the male member 4 housed within the cap or cover 20. The resiliency of the socket 19 is such as to render the attaching device being opened without mutilating the tag but is of sufficient contracting strength to securely secure the members into locking contact for the purpose for which it is intended.

15 Slight changes might be resorted to in the form and arrangement of the several parts herein described within the scope of the appended claims, without departing from the spirit and scope of my invention, hence I do 20 not desire to limit myself to the exact construction as herein set forth.

Having fully described my invention, what I claim as new and desire to secure by Letters Patent, is:

25 1. A marking tag of the character described, composed of two flap ends, one of which is provided with a pointed stem having an annular shoulder thereon, the other flap being provided with means for engaging with the said shoulder on the stem in which the said stem is confined and housed when the ends of the tag are pressed together, substantially as described.

2. A marking tag of the character described, composed of two flap ends, one of which is provided with a pointed stem, having an annular shoulder thereon and a head on the opposite end thereof, a disk provided with a central opening therein, and a plurality of slits opening thereto, the said disk being secured over the said stem and on the inner face of the said flap, the other flap end being provided with means for engaging with the said annular shoulder on the stem 40 and in which the said stem is confined and housed when the ends of the tag are pressed together, substantially as described.

3. A marking tag of the character described, composed of two flap ends, one of which is provided with a pointed stem having an annular shoulder thereon, the other end being provided with a collapsible hollow cylindrical stem provided with an opening in the upper end and a circumferential flange 55 formed on the opposite end thereof, and a

plurality of slits within the said cylindrical stem extending through the said flange, a cap, adapted to be secured on the upper end of the said hollow cylindrical stem when the said stem is collapsed therein, the said flange 60 end of the said stem adapted to engage with the annular shoulder on the first mentioned stem, whereby the said stem is retained and housed therein when the ends of the tag are pressed together, substantially as described. 65

4. The combination with a marking tag of the character described, composed of a folded card having two flap ends and a fastening device, of a pointed stem provided with an annular shoulder thereon, a head 70 provided on the opposite end of the said stem, a collapsible hollow cylindrical stem having a circumferential flange on one end thereof, and a plurality of slits within the said stem extending through the said flange, 75 a cap secured on the opposite end thereof, substantially as described.

5. The combination in a tag of the character described, comprising two flap ends, of a male member provided with a pointed 80 stem, having an annular shoulder thereon, a head provided on the opposite end thereof, and a female member comprising a hollow collapsible cylindrical stem, having a circumferential flange on one end thereof, means for 85 securing the said members to the said flap ends, substantially as described.

6. The combination with a tag of the character described, comprising a folded card having two flap ends and a fastening device, 90 of a pointed stem provided with an annular shoulder thereon, a head provided on the opposite end of the said stem, means for securing the said stem on one flap end, a collapsible hollow cylindrical stem having a circumferential flange on one end thereof, and a plurality of slits within the said cylindrical stem 95 extending through the said flange, a cap securing the said collapsed cylindrical stem on the other flap end and adapted to house the point of the first mentioned stem when the ends of the tag are pressed together, substantially as described.

In testimony whereof I affix my signature in presence of two witnesses.

IRVING KAUFMAN.
